(57) **CLAIM**

The ornamental design for a photography light, as shown and described.

DESCRIPTION

1. Photography light

FIG. 1.1 is a front, left and top perspective view of a photography light embodying our new design;

FIG. 1.2 is a rear, right and bottom perspective view thereof;

FIG. 1.3 is a front elevation view thereof;

FIG. 1.4 is a left side elevation view thereof;

FIG. 1.5 is a right side elevation view thereof;

FIG. 1.6 is a rear elevation view thereof;

FIG. 1.7 is a top plan view thereof;

FIG. 1.8 is a bottom plan view thereof;

FIG. 1.9 is an enlarged view of portion 9 shown in FIG. 1.2;

FIG. 1.10 is a reference view of one of its usage states; and

FIG. 1.11 is a reference view of another of its usage states.

This photography light is used for photography or for photography to provide lighting. The broken lines shown in the drawings depict portions of the photography light that form no part of the claimed design. The additional broken lines only seen in 1.10 and 1.11 depict environment and form no part of the claimed design. The dash dot dash broken lines depict boundaries of areas of enlargement and form no part of the claimed design.

1 Claim, 11 Drawing Sheets
